ANODE COOLING SYSTEM

Wilfrid L. Atwood, Newton Lower Falls, Mass.,
assignor to The Girdler Corporation, Louisville,
Ky., a corporation of Delaware

Application May 15, 1946, Serial No. 669,997

8 Claims. (Cl. 250—27.5)

1

This invention relates to anode cooling systems of the type particularly adapted for the cooling of the anodes of oscillators or electrical generators, and has for an object the provision of a cooling system which combines the advantages of air cooling and liquid cooling systems without their disadvantages.

In the design of radio tube oscillators or high-frequency generators, the power dissipated in the tubes presents a major problem. As the power output increases, the power dissipated in the tube in the form of heat likewise increases. Where small tubes, of low power rating, are utilized, the anodes may be radiation-cooled. As the size increases, it has been the practice to attach cooling fins and to arrange a fan to circulate air to take care of the dissipation of power at the anode. While air cooling has been utilized, it is not particularly efficient and tubes must be operated with lower rated loads than the same tubes in systems which provide water cooling. For example, a tube of the type known as the "892" has a rated dissipation of ten kilowatts if the anode be water cooled but for the same tube with fins attached to the anode and an air blower to circulate air through the fins, the rating of the tube is only four kilowatts.

When it is realized that the air cooling requires not only the fan, the motor for driving it, but also the air ducts, it will be understood water or liquid cooling would seem highly desirable. The difficulty with water cooling the tubes as usually practiced, however, is the need to provide a source of water, which preferably should be distilled or otherwise free of impurities. The usual water cooling system is heavy and cannot be used where the high-frequency generator is to be portable. Circulation of tap water ordinarily is not feasible, due to the deposition of scale and the resulting shortened tube-life.

It is an object of the present invention to provide a cooling system which is self-contained, which does not add sufficiently to the weight and volume as to prevent portability of the high-frequency generator, and which is highly efficient.

In carrying out the invention in one form thereof, there is provided a cooling system for the anode of the tube characterized by a radiator in which there is maintained a low level of water and from which the water or liquid is circulated around the anode of the tube. Air may be purged from the vapor space by a valve similar to the common type of thermostatic valve such as used in the ordinary household heating system. Such a valve would pass air but not steam. It would,

of course, readmit air on cooling. Therefore the system would never be subjected to vacuum and the seals would only have to be designed for pressure. The pressure and temperature in the vapor space rise in accordance with the well established steam tables and the increased temperature of the vapor will give a greater temperature difference between the condensing vapor and the cooling air. At some temperature and pressure the rate of condensation and the rate of evaporation will be equal. The vapor temperature will rise until this equalization occurs.

For a more detailed understanding and for further objects and advantages thereof, reference is to be had to the following description taken in conjunction with the accompanying drawing in which there is diagrammatically illustrated a system embodying the invention.

Referring to the drawing, the invention in one form has been shown as applied to a vacuum tube 10 having an anode 11 disposed within a water jacket or heat exchanger 12. Suitable sealing means is provided at 13 to form a water-tight connection between the upper end of the jacket 12 and the anode 11. The jacket 12 is always full of water 14 which circulates by way of a pipe connection 15, a length of rubber tubing 16, and a pipe 17 to a radiator 18. The radiator 18 preferably consists of a plurality of vertical tubes and fins which extend between an upper chamber 18a and a lower chamber 19 in which the water level is maintained above the point of entry of the pipe 17 therein. For example, the water level may be maintained as indicated by the water gauge 20 and the broken line 21. The return circuit for the cooling water is by way of the pipe 22, a length of rubber tubing 23, and the pipe 24 to the jacket 12. To maintain a high rate of flow of cooling liquid, a pump 25 is included in the return line forcibly to circulate water around the anode 11 and in the same direction as that due to the thermo-siphon action. The rate of flow of the cooling water is maintained high enough to insure removal of steam bubbles as fast as they may form on or around the anode 11. Since these steam bubbles will form even though the average temperature of the water leaving the jacket 12 is below the vaporizing point, it is important that they be removed at once in avoidance of hot spots. By maintaining a high velocity on the cooling water, the bubbles are swept away as rapidly as they form. Effective cooling is maintained at all times.

The radiator 18, except in respects discussed below, is of conventional design and may be gen-

erally of the type such as utilized on automobiles or as utilized in automobile heaters where the water or fluid from the radiator is circulated through the radiator tubes and heat removed by means of a fan blowing air against the water-filled tubes. In accordance with the present invention, however, vapor in the tubes of radiator 18 is cooled by means of a fan 27 driven by a motor 28. Also, it and the cooling system of which it is a part, is filled with water only to the level 21 or thereabouts, leaving a large vapor-cooling area thereabove. The radiator 18 and its associated system are sealed in avoidance of any leakage. However, a valve 32 is provided at the upper portion of the radiator to provide for outward passage of air. The valve 32 may be a vent valve of the thermostatic type now widely employed on household vapor and steam heating systems. It serves to eliminate air from the system, as the temperature rises, but prevents egress of steam. Of course, when the temperature is reduced below a certain degree, the valve opens and air again enters the system. It is more satisfactory to design the system to withstand pressure without the additional requirement that it be designed to include seals for sub-atmospheric pressures.

During operation, the temperature of the anode 11 rises as the load on the tube 10 increases. However, the forcible circulation of the water through the jacket 12 and in contact with the anode 11 maintains the anode 11 at a suitable operating temperature. This temperature, though it may differ on tubes of different design, may be in the neighborhood of 250° F. to 275° F., which means, of course, that the water entering the radiator 18 will be at a correspondingly high temperature. By reason of the high temperature within the radiator 18, there is maintained a high mean temperature difference between it and the air forced therethrough by the cooling fan 27. By reason of the high temperature, there is rapid evaporation or vaporization of the water from the surface of the liquid level 21. There is correspondingly rapid condensation of the vapors since the rate of cooling, per unit area of radiator surface, increases as the temperature within the radiator rises. In other words, the cooling effect at all times depends upon the mean temperature difference between the air and the radiator. Thus, the system is self-regulating in that as the rate of vaporization increases due to an increase in temperature, there is at the same time an increase in the rate of condensation.

During operation, the temperature of the anode 11 tends to rise. However, water is circulated through the jacket 12 at a high rate and the temperature of the water entering the radiator 18 will increase. When the temperature does rise, the evaporation or vaporization of the water from the surface of the liquid level 21 increases. With the higher resultant temperature, the vapor condenses more rapidly. Thus, the system is self-regulating in that as the rate of vaporization increases, the pressure rises correspondingly. In this manner, the level of the liquid in the radiator 18 is maintained substantially constant and well above the level of the inlet and outlet pipes 17 and 22.

Further in accordance with the invention, advantage is taken of the fact that the coefficient of heat transfer from a condensing vapor to a metal heat transfer wall is approximately four times the coefficient of heat transfer from a hot liquid to such metal heat transfer surface. Ac-

cordingly, the radiator 18 for a given application may be quite small as compared to what it would be for the same application where liquid to metal contact alone is utilized. Moreover, the cooling system is intended to operate at relatively high temperatures and materially above room temperature. For example, if the water temperature entering the radiator is 267° F., there will be a pressure of twenty-five pounds gauge in the radiator 18. With this high temperature there will be a high mean temperature difference with reference to room temperature and thus there will be provided a very effective cooling system which is relatively unaffected by variation in air temperature as from summer to winter.

Because the cooling system is small in size and compact, it may be incorporated as a unit into the high-frequency oscillator though spaced physically away from it, the only requirement being the pipe connections and the insulating rubber hose 16 and 23.

It will, therefore, be seen that the present invention combines the advantages of water-cooled tubes with their small size and increased heat dissipating capacity plus the advantage of a closed water system in which no mineral deposits will adversely affect the tube life. Since the cooling system is sealed, pure distilled water may be utilized or such other cooling liquid as may be desired which is free of scale-depositing constituents.

When it is realized that a radiator operating in accordance with the invention will have a dissipating capacity in excess of 30,000 British thermal units per square foot of radiator surface for a relatively thin radiator, of the order of three inches in depth, it will be understood that the radiator size will not be a limiting factor in the use of the cooling system. Moreover, since the water or other cooling medium is maintained in the liquid state below the level 21 in the radiator 18, which level is above both the radiator inlet and outlet, maximum safety is provided against loss of cooling liquid for the anode 11. There has been avoided the danger of formation of steam around the anode since as the temperature rises the pressure also rises and steam formation is thereby inhibited.

Should the temperature rise above a safe value, as indicated by a thermometer 30, the oscillator or generator would, of course, be shut down. If desired, the thermometer 30 may be of the contact-making type automatically to de-energize the oscillator when the temperature exceeds a predetermined value. A second thermometer 31 may be provided in the return line. If desired, a pressure-responsive switch 33 shown as comprising a bellows 34 operating against the bias of a spring 35 may be provided to de-energize the oscillator when the pressure in the radiator 18 rises above a desired value. These factors of control are simple, efficient and positive in their action and found to be desirable adjuncts to the present invention.

While a preferred form of the invention has been illustrated, it is to be understood that modifications may be made within the scope of the appended claims:

What is claimed is:

1. A cooling system comprising an anode of an electric tube having a fluid jacket sealed around the anode and a pump for circulating cooling fluid through said jacket, a radiator having in the lower portion thereof an inlet and an outlet connected in series circuit with said pump and said

jacket, said system having a fluid level above said inlet and said outlet, and said radiator providing a confined vapor space above said level in which the pressure varies with the temperature to regulate the rate of condensation of fluid received from said jacket.

2. A cooling system comprising an anode of an electric tube having a water jacket sealed around the anode, a radiator sealed from atmosphere and having in the lower portion thereof an inlet and an outlet and in the upper portion thereof a closed vapor chamber, means forming a closed system between said inlet and said outlet and said fluid jacket, and means for forcibly circulating water through said system and around said anode as a continuous stream, said radiator in the combination having the characteristic that it is self-regulating as to the rate of condensation in said vapor chamber in that the pressure varies therein with the water temperature to maintain the rate of condensation adequate to maintain said water level above said inlet and said outlet.

3. A cooling system comprising an anode of an electric tube having a water jacket sealed around the anode, a sealed radiator located with its water-level above the uppermost part of said jacket, pipe connections extending from said radiator to the upper and lower portions respectively of said water jacket, said radiator being air-tight to provide a sealed water-circulating system, said radiator also having a confined vapor space above the normal level of water therein, a fan for circulating air in heat exchange relation with said vapor space for removal of heat therefrom, means included in one of said pipe connections for forcibly circulating water therethrough and into high velocity contact with said anode, said radiator in the combination having the characteristic that the pressure within said vapor chamber is at room temperature, below atmospheric pressure.

4. The method of cooling the anode of a thermionic tube which comprises circulating liquid as a continuous stream in a closed path isolated from atmospheric pressure, at one region in said path passing the stream over the anode to effect transfer of heat therefrom and to sweep away steam bubbles that may form on the anode at a subsequent region in said path effecting evaporation from the surface of the liquid stream to cool it, collecting the vapor in a confined space to produce on the liquid enhanced pressure increasing its boiling point, cooling and recon- densing the vapor, and returning the condensate to the stream further to reduce its temperature in advance of said first-named region.

5. The method of cooling the anode of an electronic tube which comprises forcibly circulating cooling liquid, in a path closed to atmosphere, as a continuous stream which in one region of its path flows over said anode to abstract heat therefrom and at a rate high enough to insure immediate removal of gas bubbles formed at the anode, at a subsequent region along said path removing heat from the stream by evaporation from the surface thereof into a confined space bounded by metallic wall structure, passing air over the exterior of said wall structure to condense said vapors and to cool the resulting condensate to lower temperature, and returning the condensate to said stream in advance of said first-named region to reduce the temperature of the stream before again flowing over said anode.

6. A cooling system for the anode of an electronic tube provided with a cooling liquid jacket sealed about the anode, comprising a radiator disposed with its inlet and outlet above said jacket and constructed with said inlet and outlet below the level of cooling liquid therein, a flow connection from the upper portion of said jacket to said radiator inlet, a flow connection from the outlet of said radiator to the lower portion of said jacket, and a pump in one of said connections forcibly to circulate said cooling liquid as a continuous stream upwardly through said jacket at a rate insuring immediate removal of gas bubbles formed at the anode, said radiator providing above the stream of cooling liquid therein a closed evaporating/condensing chamber in which vapors rising from the stream are condensed and returned to the stream.

7. A cooling system containing a predetermined quantity of cooling liquid and adapted for the cooling of the anode of an electronic tube, including in combination a cooling liquid jacket sealed about the anode and flooded with said liquid, a radiator disposed with its inlet and outlet above said jacket and constructed with said inlet and outlet below the level of cooling liquid in the radiator, whereby said inlet and outlet of the radiator remain flooded with liquid at all times, a connection from said radiator inlet to the upper portion of said jacket, and a pump having its outlet connected to the lower portion of said jacket and its inlet connected to the radiator outlet forcibly to circulate said cooling liquid as a continuous stream passing upwardly through said jacket at high velocity to sweep away gas bubbles at the anode and thence through said radiator, said radiator providing above the stream of cooling liquid therein a closed evaporating/condensing chamber in which vapors rising from the stream are condensed and returned to the stream.

8. A cooling system for the anode of an electronic tube having a cooling jacket sealed about the anode, comprising a closed path for circulation of coolant in liquid phase including a radiator having its inlet and outlet above said jacket and having connections therefrom to said jacket, a pump in one of said connections forcibly to circulate the liquid coolant in said path upwardly through said jacket and upwardly to the radiator, said radiator having a closed evaporating/condensing chamber containing liquid coolant above said inlet and outlet and in which evaporation and condensation of the coolant are continuously effected without interruption of the continuity of said liquid path.
